UNITED STATES PATENT OFFICE.

CHARLES ALBERT YALE, OF BURLINGTON, VERMONT, ASSIGNOR TO YALE
WONDER CLOCK COMPANY, OF SAME PLACE.

DESIGN FOR A CABINET FOR COIN-CONTROLLED APPARATUS.

SPECIFICATION forming part of Design No. 34,204, dated March 12, 1901.

Application filed February 15, 1901. Serial No. 47,514. Term of patent 3½ years.

To all whom it may concern:

Be it known that I, CHARLES ALBERT YALE, a citizen of the United States, residing at Burlington, in the county of Chittenden and State of Vermont, have invented and produced a new and original Design for Cabinets for Coin-Controlled Apparatus; and I do declare the following to be a full, clear, and exact description of the same, reference being had to the accompanying drawing, forming a part thereof.

My invention relates to new and original designs in cabinets for coin-controlled apparatus.

The accompanying drawing illustrates a front elevation of a cabinet embodying my new design.

As shown in the drawing, the cabinet is provided with a plain base surmounted by a compartment having a rectangular panel bordered by triangular corner-pieces. Rising from a ledge at the top of the compartment are two side pillars, ornamented at their upper portions by longitudinal grooves and capitals and supporting a top molding. Immediately below the top molding a rectangular panel extends across the cabinet between the pillars. Below the panel are two scrolls. A series of openings are arranged in a curve

below the scrolls, and in the longitudinal center of the cabinet under these openings is a round hole immediately above a rectangular aperture. Arranged in a curve under the rectangular aperture is a scroll, and at each side of this scroll and below a portion thereof is a small opening. A circular panel is located above the ledge referred to, and an oblong opening extends centrally across the panel. Scrollwork is arranged at the corners of the panel.

The distinguishing feature of my new design is the arrangement of the circular and rectangular openings and apertures in the face of the cabinet near the top and in the circular panel below.

Having thus described my new and original design, what I claim is—

The design for a cabinet for coin-controlled apparatus, substantially as shown and described.

In testimony whereof I affix my signature in the presence of two witnesses.

CHARLES ALBERT YALE.
